Patented Nov. 26, 1901.

A. T. WAY.

EXTENSION SCREEN FOR WINDOWS OR DOORS.

(Application filed Apr. 11, 1901.)

(No Model.)

UNITED STATES PATENT OFFICE.

ABEL T. WAY, OF BURLINGTON, VERMONT.

EXTENSION-SCREEN FOR WINDOWS OR DOORS.

SPECIFICATION forming part of Letters Patent No. 687,466, dated November 26, 1901.

Application filed April 11, 1901. Serial No. 55,840. (No model.)

To all whom it may concern:

Be it known that I, ABEL T. WAY, a citizen of the United States, and a resident of Burlington, in the county of Chittenden and State 5 of Vermont, have invented certain new and useful Improvements in Extension-Screens for Windows, Doors, &c., of which the following is a specification.

My invention relates to two-part extension-10 screens which are extensible by reason of the sliding of one part upon the other.

Its object is to simplify and cheapen the construction of a screen of this kind, as well as to enhance the efficiency of the same; and 15 it consists of the parts and combinations of parts which will first be described by reference to the accompanying drawings, forming part of this specification, and will then be more particularly pointed out in the claims.

20 In the said drawings, Figure 1 is a view of the screen partly extended. Fig. 2 is an inner edge elevation of part of one of the sections of the screen. Fig. 3 is a section on line 3 3, Fig. 1. Fig. 4 is a detail of one of 25 the clips, part of one of the top rails, and part of the angle-iron strip. Fig. 5 is a detached view of the angle-iron strip which forms the inner vertical rail of each section. Fig. 6 is a detached view of one end of the covering-30 strip B'. Fig. 7 is a section on line 7 7, Fig. 5. Fig. 8 represents sectional detail views of the horizontal extensions.

Each section of the screen is the counter-part of the other in construction, so that a description of one will answer for both.

Each section-frame is composed of an outer vertical or upright rail A, top and bottom horizontal rails B B, and a sheet-metal angle-iron strip C, which constitutes the inner vertical or upright rail. The wire gauze or netting D is secured to these parts. It is secured to the end upright A by a covering-strip A' in the usual way. It is secured to the top and bottom rails B by having its edge located in 45 a longitudinal recess b, formed in each rail, and there secured by a narrow covering-strip B' of a size to fill said recess and to be flush with the body of the rail B, and it is secured to the strip C in the manner indicated in Fig. 50 7. The strip C is a strip of sheet metal of proper width which is first folded longitudinally partly over itself and upon the

edge of the wire-netting which is embraced between the folds, as shown at c, the unfolded portion of the strip, together with the sheet 55 of wire-netting, being bent at right angles to the folded limb c', the unfolded portion of the strip when thus bent forming the limb c of the angle-iron. The netting is thus held most firmly, while the folded limb c, which stands 60 at right angles to the face of the screen and which in each screen-section projects toward the face of the netting of the other section, effectually prevents flies and other insects from passing between the two halves of the 65 screen. In the inner face of each strip B' is a slot b', extending crosswise the strip, forming at the lower edge an opening b³ and registering at its upper end with an opening b², formed in said strip B'. The ends of the angle-iron 70 strip C are flattened, as shown at c², and the extreme ends are turned up as hooks, as shown at c³. When the strips B' are applied and nailed to the top and bottom rails, (which is after the angle-iron strip C is in place,) the 75 slots b' fit the flattened portions c² of the strip C, while the hook ends c³ enter the openings b², thus holding all of the parts most firmly together.

The inner end piece C of each half of the 80 screen is located some distance from the inner end of the rails B, leaving at this end of the screen-section portions of said rails B in the nature of horizontal extensions B². To these extensions B² are secured the clips E, which 85 hold the two halves of the screen together, thus furnishing a longer and smoother running bearing for the parts in their sliding motion than could otherwise be obtained. The clips E (represented in Figs. 2 and 4 as before 90 being bent) consist each of a sheet-metal rectangular piece of proper size, the shank of which is inserted and held in a slot e cut in the rail, and the protruding portion of which is then bent over so as to embrace the adjoining 95 rail of the other half of the screen, all as plainly shown in the drawings. The slot e is cut in the extension B² in the position shown in the drawings, the slot being flush with the recess b and extending outwardly therefrom 100 through the body of the rail to the outer edge of the rail and being parallel to the longitudinal side faces of the rail. When the shank of the clip is inserted in this slot it is there

held by a suitable means—as, for example, by driving a portion of the metal of which it is composed into the body of the rail, as will be understood without further explanation.

5 Having now described my improvements and the manner in which the same are to be carried into effect, what I claim herein as new and of my own invention is as follows:

1. In a two-part screen, the combination 10 with the top, bottom and outer end rails and wire-netting on each section, of an inner end rail composed of a sheet-metal strip, bent in angle-iron form, having a limb c' parallel with the face of the netting, and a folded limb c

15 which embraces between its folds the edge of the netting and projects at right angles thereto toward the face of the netting of the opposite screen-section, as and for the purposes hereinbefore set forth.

20 2. The angle-iron piece having a folded limb c , embracing the edge of the netting, and a limb c' , at right angles to said limb c and parallel with the face of the netting, said angle-iron piece having flattened end portions c^2 , 25 terminating in hook ends c^3 , in combination with the top and bottom rails B, recessed at b , and the covering-strip B', secured in recess

b , and provided with slot b' having upper and lower openings b^2 and b^3 in which are fitted the said hook ends c^3 and flattened end portions c^2 respectively, substantially as and for the purposes hereinbefore set forth. 30

3. The top and bottom rails B of each screen-section formed with longitudinal recesses b on their interior opposite faces to receive the netting covering-strips B', and having in their ends B^2 which extend inwardly beyond the inner vertical section-rails, slots e each of which starts from the intersection of the back and side of its recess and extends thence outwardly through the rail in the plane of the back of the recess, in combination with the clips E which embrace the edges of the rails B of the opposite screen-section and are provided with shanks which are inserted and secured in said slots as hereinbefore shown and described. 35 40 45

In testimony whereof I have hereunto set my hand this 9th day of April, 1901.

ABEL T. WAY.
